UNITED STATES PATENT OFFICE.

JOHN F. KELLY, OF CHICAGO, ILLINOIS.

INTERNAL-COMBUSTION ENGINE.

1,304,688.

Specification of Letters Patent. Patented May 27, 1919.

Application filed February 3, 1916. Serial No. 76,032.

To all whom it may concern:

Be it known that I, JOHN F. KELLY, a citizen of the United States, residing at Chicago, in the county of Cook and State of Illinois, have invented certain new and useful Improvements in Internal-Combustion Engines, of which the following is a full, clear, and exact specification as will enable others skilled in the art to make and use the 10 same, reference being had to the accompanying drawing, forming a part hereof.

My invention relates generally to improvements in internal combustion engines, and has reference more particularly to the provision in a working cylinder of a novel secondary explosion chamber designed to communicate with the compression space on primary explosion chamber of the cylinder and constructed and arranged for explosively 20 firing the charge contained in the said compression space.

Heretofore it has been customary in engines of this type to ignite the charge through the instrumentality of an igniting 25 device, as a spark plug. It has been found however that a deposit of carbon and oil accumulated upon and in the vicinity of the spark plug electrodes, such deposit frequently producing premature explosion of 30 the charge in the cylinder and in any event having an effect of fouling the plug to such an extent as to eventually necessitate the removal of the device. In such case where a low gravity gas was desired to be employed, 35 that is a gas having a low specific gravity (as for example say approximately 54 degrees), or where in starting the engine the surrounding atmosphere was at a low point, the igniting device has proved inefficient, 40 and in the first instance practically if not wholly ineffective.

The principal objects, therefore, of my invention are, first, to permit the extensive utilization of such so-called low gravity gas 45 in an internal combustion engine; second, to attain a maximum explosion and thorough burning of the main charge, whether of a high or low gravity; and third, to produce a more efficient starting of the engine where 50 the surrounding atmosphere is at a low point. These enumerated objects are attained in a highly efficient manner by my device, which, without possibility of failure,

explosively fires the main charge, producing thereby a maximum flash and heat unit, 55 larger and greater than heretofore produced. This device has a chambered interior provided thereabove with a spark plug or equivalent device, and is so constructed and arranged as to receive and envelop an appreciable quantity of the more ethereal portion of the gas rising to the top of the compression space in the cylinder to form an explodable secondary charge, ignition of which by the plug results consequently in an explosion in said chambered interior, or secondary chamber, of a capacity producing the desired explosive firing effect upon the main charge. Another object attained by 60 my invention, as I have found in practice, 65 is that each explosion of the secondary charge ejects or destroys any deposit remaining in the chamber from the prior explosion and therefore effectually prevents the fouling of the electrodes of its associated 70 spark plug. The device as a whole has a very efficient self-clearing characteristic. As a matter of test I have inserted a dirty spark plug in my explosion chamber and after 75 subsequent use of the same in service have 80 found on removal of the plug that it was free from that which before had fouled it.

A further object of my invention is the provision of a chamber for a spark plug adapted for application to the standard 85 tapped opening in the head of the cylinder, and wherein said chamber explosively communicates with the cylinder interior and is similarly tapped or threaded to receive the threaded portion of a standard spark plug. 90

It will thus be seen that my invention has for its chief aim to improve the construction of gas or other types of explosive engines and increase the efficiency and utility of devices of this character, this efficiency being 95 expressed particularly in increased mileage on a given quantity of gas.

These, together with such other objects as may hereinafter appear, or are incident to my invention, I attain by means of the construction illustrated in preferred form in the accompanying drawings, wherein:—

Figure 1 represents a sectional view of a cylinder head to which my invention is shown applied;

Fig. 2 is a view embodying the spark plug,

cylinder head cap and secondary explosion chamber, the cap and chamber being in section;

Fig. 3 is a view in elevation of said explosion chamber; and

Fig. 4 represents a central vertical section taken through the same.

Referring to the drawings, the numeral 5 designates in conventional form an internal combustion engine cylinder having a head 6, piston 7, and compression space 8 located intermediate the cylinder head and the top of the piston. Forming part of this cylinder head 6 is a cap 9 tapped at 9^a to provide an opening capable of receiving the threaded lower portion of a standard spark plug, such for example as the one indicated by the numeral 10 in the drawings. This stated construction, *per se*, represents nothing more than that which is well known in the art.

In the preferred construction as illustrated, my invention takes the form of a chambered fitting or device provided with an elongated chamber 11. The upper portion of this device is shouldered to constitute a nut 12, such nut being tapped at 13 to receive the lower threaded portion 14 of the spark plug 10 whose electrodes, when the plug is thus positioned, are located at the top of the chamber 11, the latter being the secondary explosion chamber to which reference has been made. Below the nut 12 and surrounding said chamber is a central wall portion or stem 15 externally threaded at 15^a whereby the device may be screwed into the tapped opening 9^a, and provided there below with the downwardly slanting openings 16 and the rounded thick ball portion 17 forming the base of the device. This base incidentally serves as a preheater for volatilizing the gas before passing into the chamber 11 through openings 16.

When the device is screwed into position, that portion carrying the openings 16 and base 17 "penetrates" into the compression space 8 of the cylinder. These openings, or ports 16 have a combined area equal to the cross-sectional area of the explosion chamber and provide direct avenues of communication between the secondary explosion chamber 11 and the said compression space, whereby, on the compression stroke of the piston 7 a quantity of the more etheral portion of the gas after passing the base is enveloped under compression in said chamber to form an explodable secondary charge, which charge on being ignited explodes and through said openings 16 explosively fires the main charge of the cylinder. Such primary explosion is of such character as to destroy or eject any deposit of carbon or oil which may have taken place, and the device therefore serves as a very practical preventive agent against acc-

cumulation of this kind in the neighborhood of the spark plug electrodes.

From the foregoing description, it will be apparent that the device is interchangeable with and capable of being used in connection with spark plugs already in service, since all that is necessary to be done in order to install my device is to first remove the spark plug from the cylinder head, screw in the device in the tapped hole 9^a and then insert the spark plug in the threaded opening provided in the upper portion 12 of the device. By rounding the base of my device all corners or pockets which might accumulate deposit are eliminated, and in providing the downwardly and outwardly slanting openings 16 I aim to produce an efficient spreading of the explosive effect for thoroughly firing and burning the main charge in the cylinder.

I do not desire to be understood as limiting myself to the precise details of construction and arrangement shown, as variations and modifications therefrom may be made without departing from the spirit and scope of my invention and improvements. I therefore reserve the right to all such variations and modifications as properly fall within the scope of my invention and improvements and the terms of the following claims.

What I claim is:

1. In an internal combustion engine having a cylinder and its spark plug, the combination of a spark plug protecting device 100 comprising an external and internal threaded hollow cap adapted for coöperation with the cylinder wall and the spark plug, the walls of the cap outside of the cylinder and within the wall of the cylinder being substantially the same thickness, whereby the interior of said cap provides within the wall of the cylinder, an elongated explosion chamber of slightly less diameter than the diameter of that portion of the explosion chamber lying outside of the cylinder, said cap being provided with a plurality of apertures opening within the cylinder laterally of the explosion chamber within the cap, the area of said aperture being substantially equal to the area of the explosion chamber.

2. The combination with the primary combustion chamber of an automobile cylinder and its standard plug orifice, and a spark plug therefor, of a device of the character described comprising an internally threaded socket portion adapted to receive the threaded base of said spark plug above said orifice, and a thin tubular body portion externally threaded to engage in said plug orifice and having a closed lower end and an elongated bore extending from the base of the plug to said closed lower end, and constructed to serve as an explosion cham- 130

ber for said primary chamber and a scavenging means for said plug, the side wall of said body portion above said closed end formed with a plurality of ports disposed in said primary chamber below said orifice and capable of providing free, direct and unrestricted charging and firing communication between the bore and the primary chamber, said device designed as a whole to

be screwed downwardly into said orifice 10 and having its threaded portions constructed of the same diameter, substantially as described.
